(57) **CLAIM**

The ornamental design for a bracelet, as shown and described.

DESCRIPTION

FIG. 1 is a top plan view of a first embodiment of a bracelet showing our new design;

FIG. 2 is a bottom plan view thereof;

FIG. 3 is a side view thereof;

FIG. 4 is an opposite side view thereof;

FIG. 5 is another side view thereof;

FIG. 6 is a perspective view thereof;

FIG. 7 is a top plan view of a second embodiment of a bracelet showing our new design;

FIG. 8 is a bottom plan view thereof;

FIG. 9 is a side view thereof;

FIG. 10 is an opposite side view thereof;

FIG. 11 is another side view thereof; and,

FIG. 12 is a perspective view thereof.

The broken lines shown in FIGS. 1 through 6 illustrate portions of the bracelet that form no part of the claimed design. The other broken lines showing a device in FIGS. 1-12 represent environmental subject matter only and form no part of the claimed design.
